UNITED STATES PATENT OFFICE.

CHARLES A. SKENE, OF WESTMORELAND, KANSAS.

WAGON-BRAKE SHOE.

SPECIFICATION forming part of Letters Patent No. 234,435, dated November 16, 1880.

Application filed July 16, 1879.

To all whom it may concern:

Be it known that I, CHARLES A. SKENE, of Westmoreland, in the county of Pottawatomie and State of Kansas, have invented a new and 5 Improved Wagon and Carriage Brake, of which the following is a specification.

The object of my invention is to furnish an improved wagon or carriage brake-block which shall be simple in construction and permit of 10 readily changing or renewing the shoe.

It consists of a block of wood or other suitable material, to which a fixed plate and a sliding plate, both provided with dovetail flanges, between which the shoe is clamped, are attached in such a manner that by means of a set-screw the shoe may be loosened or retained, all the parts being constructed and arranged as hereinafter more fully described and claimed.

In the accompanying drawings, Figure 1 is 20 a front elevation of the block. Fig. 2 is a vertical longitudinal section on the line *x x*. Fig. 3 is a horizontal cross-section on the line *y y*.

Similar letters of reference indicate corresponding parts.

25 A is a block of wood or some other suitable material, and is mortised for the reception of the cheeks J and K, attached to the plates C and D, respectively. The plate C is securely fastened to the block A by the screws N N, or some other suitable means, and the 30 plate D is fastened by the screw O, which passes through the slot M, and thus allows it to move to and from the plate C.

The slide D is adjusted by the screw H, which 35 passes through the cheeks J and K and into the block A.

The cheek K is provided with a threaded screw-hole, E, but the cheek J has a recess, R, the sides and top of which fit closely into 40 an annular groove, L, in the shank of the screw. If the screw is turned, it cannot move in either direction, as it is held by the cheek J; but the screw taking in the threads of the hole E will cause the cheek K, and with it

the slide D, to move to or from J, according 45 to the direction in which the screw is turned.

B represents a brake-shoe of leather, rubber, or some other similar or suitable elastic material.

The parts C and D are first drawn apart, 50 the shoe is inserted, and the screw H drawn tight, thereby causing the parts D and C to approach and the shoe to be firmly clamped between their dovetail flanges.

The angular bars P P are to prevent the 55 shoe from being drawn down by the wheel when the friction is very great.

The shoe, block, and the several parts may be made of wood, iron, steel, or some other suitable material. The blocks are to be so arranged that the heads of the screws are to the inner side of the wheel. Without any inconvenience and without much time or labor the 60 shoes can be renewed or adjusted.

The plates form a very slight dovetail, so that 65 when the brake is applied the wheel forces the shoe down into this dovetail.

I am aware that it is not new to make a brake-block movable or adapted to suit the dishing of the wheels; but my invention is simply a means of attaching and holding a rubber upon the face of a brake-block so as to take 70 up wear and allow the easy replacement of the rubber.

What I claim as new is—

75 The combination of the mortised block A, stationary flanged plate C, having cheek J, adjustable flanged plate D, provided with cheek K, elastic shoe B, and adjusting-screw H, having annular groove L, the said plates being also 80 provided with angular bars P P, adapted to embed themselves in the body of the shoe and hold the same securely against frictional strain, substantially as set forth.

CHARLES A. SKENE.
